WRENCH

Walter R. Meier, Hamburg, and Hollis R. Ross, Buffalo, N. Y., assignors to Barcalo Manufacturing Company, Buffalo, N. Y.

Application November 23, 1955, Serial No. 39,019

Term of patent 14 years

(Cl. D54—13)

Fig. 1 is a perspective view of a wrench showing our new design;

Fig. 2 is a plan view thereof;

Fig. 3 is a side elevational view thereof;

Fig. 4 is a transverse sectional view thereof, to a larger scale, taken along line IV—IV of Fig. 3; and

Fig. 5 is a fragmentary plan view thereof taken about along line V—V of Fig. 3.

We claim:

The ornamental design for a wrench, as shown.
